UNIFORM MUZZLE VELOCITY
PNEUMATIC GUN

William S. Wells, Palo Alto, Calif., assignor to
Daisy Manufacturing Company, Plymouth,
Mich., a corporation of Michigan

Application August 4, 1949, Serial No. 108,566

12 Claims. (Cl. 124—13)

1

This invention relates to pneumatic guns and more particularly to a repeating type pneumatic gun which will shoot a plurality of shots from a single compressed air charge, at a substantially constant velocity, and is a continuation in part of applicant's copending application for improvements in Mechanism for Maintaining Substantially Uniform Muzzle Velocity for Pneumatic Guns, Serial No. 762,391, filed July 21, 1947, and now abandoned.

The pneumatic gun of this invention is provided with a storage chamber in which fluid under pressure is held for use in propelling shot, either of the ball or pellet type, through the gun barrel, at high velocities. The air in the chamber may be periodically replenished by suitable compressor means, forming either a part of or a separate unit from the gun itself. Valve means are provided for controlling the flow of air from the storage chamber to the gun barrel behind a projectile therein, and the valve is operated in a novel manner through a trigger mechanism and hammer mechanism. The gun of this invention will fire a plurality of shots, after the storage chamber has been charged, at substantially the same muzzle velocity. The number of shots fired from a single air charge may be varied, and the gun of this invention can be arranged to shoot from one to one hundred shots, all at substantially the same velocity, without recharging the air chamber. The number of shots which can be fired from a single air charge depends upon the number of shots the gun is designed to fire.

In the past fifty years many people have attempted to produce a repeater type of air gun. It should at this time be pointed out that the word "repeater," as used herein, means a gun which will shoot a plurality of shots, from a single air charge, all at a substantially uniform muzzle velocity. No one has heretofore succeeded in developing a repeating, self-contained pneumatic gun. Many people have, of course, developed pneumatic guns which will fire more than one shot from a single air charge, but such guns are not repeaters because the muzzle velocity of the plurality of shots is not substantially uniform. The gun of this invention is designed primarily to shoot projectiles at relatively high velocities. Such guns are quite generally used as target guns and must, therefore, be extremely accurate. If a plurality of projectiles are shot from a gun, and the muzzle velocities thereof vary materially, the accuracy of the gun is destroyed and the gun is not satisfactory as a target gun.

2

While guns have been developed in the past, which claim to be of the repeater type, none of these guns is a repeater in the sense referred to above. In one type of previously developed "repeater" gun, a valve is provided between the air storage chamber and a passageway leading to the gun barrel. This valve is resiliently held in its closed position by means of a spring and the valve is adapted to be opened, against the spring, by means of a spring actuated hammer. In this construction the valve spring is stronger than the hammer spring, so that the valve spring will close the valve after it has been opened by the impact of the hammer against the valve stem. Thus, the valve will be opened substantially the same amount each time it is hit by the hammer and as there is a fixed volume and pressure of air in the storage chamber, the pressure of air in the storage chamber will become less after each opening of the valves. As the valve opens the same distance and for the same length of time, each time, the same volume of air will flow into the gun barrel each time the valve is opened, and the volume of air will be at a lesser pressure each time the valve is opened. Thus, as a constant volume of air of a continually diminishing pressure, flows into the gun barrel each time the valve is opened, the muzzle velocity of each successive projectile which is shot from the barrel will be materially less than the previously shot projectile. Thus, the gun is not accurate and is not, in effect, a repeater, even though the gun may be able to shoot more than one projectile.

Another previously developed gun which claims to be, but is not a repeater, is constructed so that the control valve opens against and is closed by the pressure of air in the storage chamber, rather than by means of a spring, as in the construction described above, and uniform muzzle velocity of a plurality of projectiles cannot be obtained. In this construction the hammer, which strikes the valve stem to open the valve against the air pressure has its throw mechanically stopped so that the air pressure in the storage chamber alone is not relied upon to stop the hammer throw or absorb the momentum and energy of the hammer. Therefore, the valve will open substantially the same amount each time it is struck by the hammer, and irrespective of the pressure of air in the storage chamber. Furthermore, in this construction the spring which actuates the hammer follows the hammer through its entire movement, even after it has struck the valve stem. Thus, when the air pressure in the storage chamber

starts to close the valve, it must overcome the force exerted by the hammer spring, thus slowing down the closing operation and allowing such a great amount of air to go into the gun barrel that from a practical standpoint the gun cannot act as a repeater. Still further, in this construction the heavy hammer and spring which are employed open the valve such a great distance that even if a large storage chamber were provided, practically all of the air would escape therefrom on the first opening of the valve. However, even if the hammer weight and hammer spring rate were reduced so as not to cause this latter condition, the gun would not operate as a repeater because the muzzle velocity of successive projectiles which are shot from the gun will drop considerably. As projectile muzzle velocity is a function of the air pressure and volume which is applied thereto, and as the valve of this gun opens substantially the same amount each time it is struck by the hammer, irrespective of the pressure in the storage chamber, uniform muzzle velocity cannot be obtained, even though more than one projectile can be shot from a single air charge.

The gun of this invention incorporates, as do the guns shown in previously discussed patents, a control valve which is actuated and opened by a spring actuated hammer. The valve is normally held in its closed position by the air pressure in the storage chamber, although a very light spring is provided to hold the valve in its closed position when no air pressure is present in the storage chamber. When the trigger mechanism of this gun is actuated, the hammer spring throws the hammer forwardly toward the valve stem, but the spring does not follow the hammer through its entire movement. Therefore, what might be termed a free-floating hammer is provided, which strikes the valve stem through the medium of an anvil so as to open the valve against the air pressure in the storage chamber. The forward movement of the hammer is stopped almost entirely by the air pressure in the storage chamber and mechanical means are not relied upon to stop the hammer movement, as in certain of the previous constructions discussed. Therefore, the distance the valve opens will vary as the pressure in the storage chamber decreases. As the pressure in the storage chamber decreases, the valve opens further and for a greater length of time, to permit a greater volume of air to flow to the gun barrel for propelling the projectile therefrom.

As the muzzle velocity of the projectile is in effect a function of the air pressure and the time the valve remains open, or the volume of air which escapes into the gun barrel behind the projectile, and as the hammer weight and hammer spring rate are properly calibrated, the pressure of air and time the valve remains open are so coordinated as to produce a substantially uniform muzzle velocity. Furthermore, as the hammer spring is not acting against the hammer when the latter strikes the valve stem or anvil, the valve can be quickly closed by the air pressure in the storage chamber and the force exerted by the spring need not be overcome before the valve can be closed. Thus, the gun of this invention is constructed and calibrated in such a manner as to enable a plurality of projectiles to be propelled therefrom, after the air chamber has been charged, at a substantially uniform muzzle velocity, thereby, for the first time providing an air gun which is actually of the repeater

type. From actual tests conducted with the gun of this invention, it has been found that the muzzle velocities of a plurality of shots, whether they be 10, 25, 50, etc., will not vary over ten percent and generally the variation between the muzzle velocities of the shots will be less than five percent. With guns of the previously developed type, as described before, if more than one shot is obtained, from a single air charge, the variation in muzzle velocities of the projectiles is extremely high, and several shots can be obtained only if the gun is pumped an excessive and impractical number of times, so as to provide a very high air pressure in the storage chamber.

It is therefore an object of this invention to provide a hand-carriable, repeating type pneumatic gun, of the aforementioned type, which will fire a plurality of projectiles, from a single air charge, at a substantially constant velocity.

It is a still further object of this invention to provide a novel and simple mechanism for a pneumatic gun of the aforementioned type, which will permit a plurality of projectiles to be shot at a substantially uniform muzzle velocity.

It is a still further object of this invention to provide a pneumatic gun of the aforementioned type, which is more durable in use, rugged in construction, and more accurate in operation than any pneumatic gun heretofore known.

These and other objects of this invention will become apparent from the following detailed description, taken in conjunction with the accompanying drawings, in which:

35 Fig. 1 is a fragmentary longitudinal sectional view through a pneumatic gun embodying the features of this invention;

Figs. 2 to 7 inclusive are respectively cross sectional views taken on the lines 2—2, 3—3, 4—4, 40 5—5, 6—6 and 7—7 of Fig. 1;

Fig. 8 is a fragmentary side elevational view of the breech end of the gun;

Fig. 9 is a longitudinal sectional view through the construction shown in Figure 8;

Fig. 10 is a cross sectional view taken on the line 10—10 of Figure 9;

Fig. 11 is a detail perspective view of the hammer shown in Figure 9;

Fig. 12 is an elevational view of the breech end of the gun;

Fig. 13 is a fragmentary perspective view of a part of the firing valve assembly;

Fig. 14 is a fragmentary longitudinal sectional view through a pneumatic gun, illustrating a further embodiment of this invention;

Fig. 15 is an enlarged sectional view of the structure illustrated in Fig. 14, taken along the line 15—15 thereof;

Fig. 16 is an enlarged sectional view of the structure illustrated in Fig. 14, taken along the line 16—16 thereof;

Fig. 17 is an enlarged sectional view of the structure illustrated in Fig. 14, taken along the line 17—17 thereof; and

Fig. 18 is an enlarged sectional view of the structure illustrated in Fig. 14, taken along the line 18—18 thereof.

Referring now to the drawings and more particularly to Figs. 1—13 inclusive, it will be seen that a pneumatic gun of the rifle type, which simulates in appearance an orthodox, well-balanced firearm, is provided. It will be understood, however, that the mechanism of this invention may be employed in pneumatic pistols or other types of weapons of a different design from that

illustrated and described. The pneumatic gun comprises a stock 11, and a frame 12, suitably secured to the stock by any suitable means, such as screws 13. The frame 12 comprises a barrel 14, a main storage chamber 15 and a secondary storage chamber 16, communicating with the main chamber 15 through a port 17.

The barrel 14 has a bore of sufficient size to receive shot of either the ball or pellet type, and this shot may be inserted into the breech end of the barrel through a suitable opening 18. In Fig. 1 of the drawings, a pellet type shot 19 is illustrated in the breech end of the barrel and this shot is preferred in instances such as target shooting, where maximum accuracy is required. The pellet 19 is formed with a relatively thin skirt 20 at the trailing end and this skirt 20 is normally flared outwardly. The maximum normal diameter of the skirt 20 exceeds the diameter of the bore and is contracted when inserted into the bore to insure circumferential contact between the skirt and the inner surface of the bore. The skirt is relatively thin and the pressure of propelling air introduced into the barrel behind the pellet tends to expand the skirt outwardly against the inner surface of the bore to provide a seal. As a result, leakage of air under pressure past the pellet is negligible and the pellet is accurately guided along the barrel. It will further be noted from Figs. 1 and 5 of the drawings, that the usual front and rear sights 21 and 22 respectively, are mounted on the muzzle and breech ends of the barrel.

The storage chamber 15 is positioned below the barrel 14 and between the barrel and secondary chamber 16. The breech or rear end of the chamber 15 is connected to a tubular compartment or chamber 24, through the front wall 24' thereof, by means of a bore 25, having the front end portion thereof enlarged to provide a passageway 26. A vertical passageway 27 connects the passageway 26 intermediate the ends thereof, to the barrel 14 at a point ahead of the pellet receiving opening 18, and enables air under pressure to flow from the storage chamber 15 to the barrel, rearwardly of the pellet 19, in a manner which will be hereinafter described.

The flow of air under pressure from the storage chamber 15 to the barrel 14 is controlled by a valve 28, comprising a plunger 29 and a valve member or pad 30. The pad 30 is suitably secured to the rear end of the plunger 29 and is formed of a wear-resisting deformable material such as, for example, rubber, synthetic rubber, or some other equivalent material. The plunger 29 is slidably supported in the rear end of a hand-operated compressor assembly 32, so that the pad 30 will normally engage the front face of the tubular compartment wall 24' and close the entrant end of the passage 26. That is, the front face of the tubular compartment wall 24' provides a valve seat 31 for the valve member or pad 30. Owing to the pliable nature of the material from which the valve member 30 is made, the latter intimately engages the seat 31 and assures a tight seal, regardless of irregularities in the adjacent surfaces of either the valve seat or valve member. It will also be noted that the valve 28 is constructed so as to enable practically instantaneous opening thereof, in a manner which will be hereinafter described, to admit fluid under pressure to the gun barrel.

While any suitable type of compressor may be provided for compressing air in the storage chamber 15, the compressor 32 which is illus-

trated, forms a unit with the gun and is manually operable to supply fluid under pressure to the storage chambers 15 and 16. The compressor 32 comprises a cylinder 33 and a piston assembly 34, which is slidably supported in the cylinder. The front end of the cylinder is closed by a cap 35, which is removably secured in place by a set screw 36. The cap 35 is centrally apertured so as to slidably receive a rod 37. The rear end of the rod 37 is connected to the piston assembly 34 for universal movement relative thereto, and the front end of the rod 37, outwardly of the cap 35, is provided with a hand grip or knob 38.

The piston assembly 34 comprises a sleeve 39, having a sealing washer 40 frictionally engageable with the wall of cylinder 33 and secured to the rear end of the sleeve 39 by a stud 41, having a passage 42 therethrough registering with the bore of the sleeve. The rear end portion of the rod 37 is reduced at 43 and a head 44 is formed on or connected to the reduced portion 43 at the rear thereof. The head 44 is slidably supported in the bore of the sleeve 39 and is conical in shape, so as to act as a valve member for closing the stud passageway 42. The extent of sliding movement of the head or valve member 44 is limited by a pin 45 threaded into a tapped opening in the sleeve 39, adjacent the front end thereof. The inner end of the pin 45 projects into the bore of the sleeve 39 between the head or valve member 44 and the shoulder 46 on the rod 37, formed by the reduced portion 43.

The rear end of the cylinder 33 is formed with a rearwardly projecting nipple portion 47, having a passageway 48 therethrough, aligned with the passageway 42 on the stud 41 and normally closed by a check valve 49. The check valve 49 includes a valve stem 50 which is housed in a tubular cage 51. The front end of the cage 51 is internally threaded for threadably engaging the nipple 47 and an annular shoulder 53 extends inwardly from the peripheral wall of the cage 51, at a point axially rearwardly from the nipple 47. The front end of the valve stem 50 extends into the nipple passageway 48 and the rear end of the stem projects through the annular shoulder 53. An enlargement or valve head 54 is provided on the valve stem 50 intermediate the ends thereof, and a washer 55 of yieldable material, is positioned on the valve stem, in an abutting relationship with the front face of the enlargement 54, for contact with the adjacent rear end of the nipple 47, to close the passageway 48. A coil spring 56 surrounds the valve stem 50 between the enlargement 54 and the annular cage shoulder 53, for normally holding the valve 49 against the rear face of the nipple in a closed position. The front end portion of the valve stem 50 is tapered so that air displaced by the piston assembly may be discharged through the passageway 48, as soon as the valve 49 is opened against the action of the spring 56.

Referring now to the operation of the compressor assembly 32 and assuming that the parts thereof are in the position shown in Fig. 1 of the drawings, it will be seen that as the rod 37 is moved axially forwardly, the head 44 moves in a corresponding direction relative to the piston sleeve 39, so as to open the passageway 42. The head 44 thus engages the pin 45 and imparts a corresponding forward movement to the piston assembly 34. During the forward movement of the piston assembly 34, air from the atmosphere is free to pass through the sleeve 39, around the head 44 and through the passageway 42, into the

cylinder 33, rearwardly beyond the piston. In this connection, it will be noted that the head 44 is formed with a plurality of flutes 44' enabling the air to flow around the head 44. After the rod 37 is moved to its forwardmost position, it is pushed inwardly and the initial rearward movement of the rod engages the head 44 thereof with the forward end of the stud 41, so as to close passageway 42. In this manner, air is trapped in the cylinder rearwardly of the piston assembly 34 and continued rearward movement of the rod 37 imparts a corresponding movement to the piston assembly so that the air is compressed in the cylinder rearwardly of the piston. The air under pressure actuates the check valve 49, when the force thereof exceeds the force of the spring 56, and the check valve is opened permitting the fluid under pressure to pass into the storage chambers 15 and 16. At the end of the rearward stroke of the rod 37, and piston assembly 34, the check valve 49 closes, trapping the compressed air in the storage chambers.

The compressor assembly 32 enables the storage chambers 15 and 16 to be replenished with air under substantial pressure, in a minimum length of time and with very little or no loss of air due to leakage. It will also be noted that provision is made for maintaining the rod 37 in its rearwardmost position when it is not in use. As is shown in Figs. 1-3 inclusive, a key 58 is formed on the rod 37 and a corresponding slot 59 is formed in the cap 35. The arrangement is such that forward movement of the operating rod is prevented until the key 58 is aligned with the slot 59.

The valve plunger 29, previously described, is slidably supported in the rear end of the compressor cage 51. The wall of the cage 51 is formed with an elongated slot 57, for receiving a lug 61 projecting radially outwardly from the outer periphery of the plunger 29, so as to hold the valve plunger 29 in an assembled relationship with the cage 51 and at the same time prevent rotative movement of the valve plunger relative to the cage. The valve plunger 29 is yieldably held in a position at the rear end of the cage, so that the pad 30 thereon engages the valve seat 31, by means of a light coil spring 62, which is disposed in the cage 51 between the shoulder 53 and valve plunger 29. The spring 62 is provided for holding the valve pad 30 in its closed position with respect to the passageway 26, when there is no fluid pressure in the storage chambers, but when fluid is compressed in the chambers it provides the major force effecting the closing of the valve, and the force exerted by the spring 62 is negligible as compared to the force exerted by the compressed fluid.

Forward movement of the valve 28, to an open position, connects the storage chambers 15 and 16 to the gun barrel 14, rearwardly of the positioned projectile 19, for propelling the projectile outwardly through the barrel. In order to open the valve 28 the desired amount, as will herein-after appear, a plunger or stem 60' is provided, which extends through bore 25 and is slidably supported in the wall 24' of the compartment 24. The length of the plunger or stem is such that the rear end portion thereof projects into the hollow interior of the compartment 24 and the front end portion thereof extends axially through the enlarged passageway 26 into abutting engagement with the valve pad 30. A head 61' is formed on the plunger or stem 60', intermediate the ends thereof, and is positioned in the passageway 26. The head 61' acts as a stop to limit rear-

ward movement of the plunger or stem 60' and serves as a seal to prevent the escape of air from the passageway 26 into the compartment 24.

The rear end portion of the plunger 60', which projects into the interior of the tubular compartment 24, is engaged by the front face of an anvil 64, which is slidably disposed in the compartment 24 and is secured to the front end of a rod 65. The rod 65 extends axially of the compartment 24 and the rear end thereof is slidably received in a recess or bore 66, formed in a plug or closure 67 in the rear end of the compartment 24. The length of the recess or bore 66 is greater than the distance between the anvil 64 and the adjacent back face 68 of the compartment wall 24' so that the rod will not become disengaged from the bore or recess 66.

The anvil 64 is adapted to be struck and actuated by a sleeve-like hammer 69, which is slidably mounted on the rod 65 and has a head portion 70 formed at the rear thereof. The hammer 69 is actuated or thrown forwardly toward the anvil 64, by a coil spring 71, which surrounds the rod 65 between the hammer head 70 and the closure 67. The coil spring is constructed so that when it has expanded to its full length, in moving the hammer toward the anvil, it will become disengaged from the back face of the hammer prior to the engagement of the hammer with the anvil. It should, furthermore, be noted that the hammer is in effect, of the free floating type, that is, it is thrown forwardly by the spring 71 and moves out of engagement therewith prior to striking the anvil 64, and is guided during its axial movement by the rod 65 and the wall of chamber 24. The forward motion of the hammer 69 is stopped almost entirely, and for all practical purposes by the storage chamber fluid pressure, acting against the valve 28, after the same has been opened by the momentum of the hammer, anvil, and valve stem or member 60'. This is of considerable importance, as will hereinafter more fully appear.

The hammer 69 is held in its rearwardmost position, wherein the spring 71 is compressed, by a trigger sear 72 pivotally mounted on the frame 12, below the compartment 24, by a pin 72', for swinging movement about an axis extending at right angles to the path of travel of the hammer 69. The swinging end of the sear 72 is bifurcated and one furcation 73 thereof projects upwardly through a slot 74 in the adjacent wall of the compartment 24, for engaging the front face of the hammer head 70, when the latter is in its retracted position, as shown in Fig. 1.

The sear 72 is operated by a trip lever 75, which is pivotally supported rearwardly of the sear on a pin 76, mounted in the frame 12. The trip lever 75 has an arm portion 77 which extends forwardly between the furcations of the sear 72, as well as a depending arm 78, which projects through a slot 79 in the gun frame 12 for engagement with a trigger 80. The trigger 80 is supported for sliding movement on a trigger guard 81, which is suitably secured to the under side of the gun stock 11 by screws 82. The trigger is provided with a lug 83, which projects upwardly through an elongated slot 84 in the gun stock to a position in advance of the arm 78 on the trip lever 75. A suitable leaf spring 85 is provided which tends to swing the trip lever 75 in a clockwise direction, as viewed in Fig. 1, with the result that the trip lever arm 77 holds the furcation 73 of the sear 72 in the path of

the head 70 of hammer 69, and the trip lever arm 78 coacts with the lug 83 on the trigger to hold the latter in its forwardmost position.

The hammer 69 is retracted to its cocked position by a plug 86 supported on the gun frame at the breech end of the barrel, for sliding movement fore and aft thereof. The top wall of the tubular compartment 24 is formed with a slot 87 extending rearwardly from the breech of said barrel 14 to the rear end of the compartment, where it is closed by the plug 67. The opposite sides of the plug 86 are formed with grooves 88 for respectively slidably receiving the opposite longitudinal edges of the slot 87, as shown in Fig. 6 of the drawings. The plug 86 is assembled on the gun frame prior to the assembly of the plug 67 by positioning the block upon the breech end of the compartment 24 with the grooves 88 aligned with the opposite longitudinal edges of the slot 87. The block 86 is then slipped on the top wall of the compartment 24 with the opposite longitudinal edge portions of the slot 87 respectively engaging in the grooves 88 in opposite sides of the block. The plug 67 is then inserted into the rear end of the compartment 24.

A stop or lug 89 is secured to the under side of the block 86 in a position to engage the front side of the hammer head 70, upon rearward movement of the block, so as to retract the hammer 69 and compress the hammer spring 11. The block 86 is moved rearwardly by an inverted substantially channel-shaped cap 90 extending longitudinally of the gun frame, to normally conceal the shot-receiving opening 18 and the slot 87. Side flanges 91 of the cap extend downwardly along opposite sides of the tubular compartment 24, and respectively slidably engage in suitable ways formed by strips 92 fixed to opposite sides of the compartment 24. The cap 90 provides a convenient grip to enable sliding of the block 86, and is connected to the block by a screw 93. The screw 93 threadably engages the cap 90 and projects into a slot 94 formed in the block 86. The front end of the cap 90 projects over the projectile opening 18 and abuts a shoulder 97 formed on the breech end of the barrel. The shoulder 97 serves to locate the cap 90 in its forwardmost position wherein the block 86 engages a stop 98 formed by the rear end of the barrel.

The block 86 also operates a positioning pin 99 which is slidably supported in the barrel at the breech end thereof and which has its rear end fixed to the block by any suitable means. The length of the positioning pin is such that when the block 86 is in its forwardmost position against the stop 98, the front end of the pin extends forwardly beyond the passage 27, so as to position the projectile 19 in the barrel ahead of the passage 27. The forward end 100 of the pin is reduced in diameter so as not to interfere with the flow of air from the passage 27 into the barrel behind the projectile. The shot receiving opening 18 is so located that when the block 86 is in its retracted position, the front end of the positioning pin 99 assumes a position to the rear of the opening so as to permit a projectile 19 to be inserted into the barrel through the opening 18. Other means, such as will be hereinafter described, may be provided for loading and positioning a projectile in the barrel so that a projectile need not be manually placed in the barrel each time it is desired to shoot the gun.

In operation, with the gun in its uncocked position and with no air pressure in the storage

chambers, the first step required to place the gun in an operative or firing position is to introduce air into storage chambers 15 and 16. This may be readily accomplished by placing the gun in an inverted vertical position with the knob or grip 38 resting on the top of a table or other suitable support and by reciprocating the gun with one hand while holding the knob 38 against the table with the other hand. It will, of course, be understood that the rod 37 is angularly adjusted prior to the above operation to align the key 58 on the rod with the recess 59 in the cap 35, so that the piston assembly 34 may, in effect, be reciprocated in the cylinder 33. As the piston assembly 34 is, in effect, moved toward the valve 49, air is compressed in the cylinder 33 and when the pressure of the air exceeds the force of the spring 56, the valve is opened permitting air under pressure to escape through the passage 48 into the storage chambers 15 and 16. On the other hand, when the piston assembly 34 is in effect moved in a direction away from the valve 49, the latter is closed by the spring 56 preventing the reverse flow of air through the passage 48. The above pumping action is continued until the desired air pressure is obtained in the storage chambers, and while this pressure may vary considerably, nevertheless, it will be assumed that a pressure of approximately 450 pounds per square inch is obtained in the storage chambers.

The gun may then be cocked by moving the cap 90 rearwardly from the position thereof shown in Figure 9 of the drawings. Rearward movement of the cap 90 imparts a corresponding movement to the block 86 and the positioning pin 99. As the block 86 moves rearwardly the projection or screw 93 engages the head 70 on the hammer 69 and slides the latter rearwardly along the rod 65. As the head 70 passes over the furcation 73 on the sear 72, the latter is swung downwardly against the action of the spring 85 and the spring 71 is compressed. When the head 70 assumes a position rearwardly beyond the furcation 73, the sear 72 is again swung upwardly to return the furcation 73 to a position in advance of the head 70 where it acts as a stop to hold the hammer in its cocked position.

In the rearwardmost position of the block 86 the positioning pin 99 is withdrawn to a position wherein the front end 100 assumes a position in the barrel 14 rearwardly beyond the opening 18, and the latter is uncovered by the cap 90. A shot such, for example, as a pellet 19, is inserted into the barrel 14 through the opening 18, and the cap 90 is moved forwardly until the front end thereof abuts the shoulder 97. The block 86 is, of course, moved as a unit with the cap, and the pellet 19 is advanced by the positioning pin 99 to a position in the barrel 14 in advance of the passage 27.

Upon completion of the above operation the gun is in condition for firing and this may be accomplished by sliding the trigger 80 in a rearward direction. As the trigger is moved rearwardly the lug 83 cooperates with the arm 78 on the trip 75 to rotate the latter in a direction to again swing the sear 72 downwardly against the action of the spring 85 and disengages the furcation 73 from the head 70 on the hammer 69. As a result, the spring 71 throws the hammer 69 forwardly against the anvil 64, and the force of the blow on the anvil is transmitted to the valve 28. The spring 71 is calibrated to apply sufficient force to move the head 30 of the valve

off the seat 31 and permit air under pressure from the storage chamber 15 to escape into the gun barrel 14 behind the pellet 19. Thus the pellet 19 is propelled through the barrel at a very high velocity depending upon the amount of air under pressure admitted to the barrel for a given static pressure in the storage chambers.

As has been previously pointed out, there are several factors which affect the operation of the gun and which make the difference between a practical repeating type gun and a gun which, although capable of firing several shots from a single air charge, is not a repeater. These factors include such things as the weight of the hammer, the K factor or stiffness coefficient of the hammer spring 71, the manner in which the hammer is actuated by the spring 71 and the manner in which the forward momentum or energy of the hammer is stopped or absorbed. Certain of these factors, such as spring K factors and hammer weights, may vary in accordance with the number of projectiles it is desired to shoot from a single air charge, the capacity of the storage chambers 15 and 16, the pressure of air in the storage chambers, etc. A specific example of the relationship of these various factors will now be set forth, but it is to be understood that these factors may be varied within predetermined limits, in accordance with the above mentioned conditions. In the following example, the gun is constructed in the following manner: the hammer spring 71 has a stiffness coefficient or K factor of 3.12 pounds per inch; the spring 62 has a stiffness coefficient or K factor of 2.81 pounds per inch; the spring 71 is compressed before firing, from its free length, a distance of $1\frac{1}{4}$ inches and is at a free length after firing or actuating the hammer; the spring 62 is initially compressed from its free length before firing a distance of $1\frac{19}{32}$ inches; the pressure of air in the storage chambers 15 and 16 is 450 pounds per square inch; the weight of the hammer 69 is .06 pound, and the mass is therefore $.06/32$ slug; the total weight of the plunger or valve stem 60, anvil 64 and rod 65 is .0467 pound, or a mass of $.0467/32$ slug; and the face area of the plunger or valve stem 60' is .0472 square inch. From this data the amount of compression of spring 62, from its free length to its length after firing, can be calculated, and is 1.658 inches. The distance the firing valve 28 opens is, therefore, the difference between the final compression of the spring 62 and the initial compression thereof, or .064 inch. These are, of course, theoretical figures, but from actual tests run on a gun constructed in accordance with the above factors, it was found that the firing valve 28 opened .062 inch.

From the above data, the total time the firing valve remains open can also be calculated, and with a storage chamber pressure of 450 pounds per square inch the firing valve will remain open .00445 second. Knowing the face area of the skirted end of the pellet in the barrel and the mass of the pellet in the barrel, the time the firing valve remains open, and the fluid pressure in the storage chambers 15 and 16, the muzzle velocity of each of a plurality of pellets, which are shot from a single air charge in the storage chambers, can be calculated. If the gun is fired twelve times, without recharging the storage chambers 15 and 16, the pressure in the storage chambers will drop, and as the pressure decreases, the spring actuated hammer 69 will open the valve 28 a progressively larger amount.

Due to the fact that the mass of the hammer 69 and the amount of compression of the spring 71 remain constant at all times, and due to the fact that there is nothing to stop the forward throw or momentum of the hammer 69 and absorb the energy thereof, except the fluid pressure in the storage chamber, and the spring 62 which has a negligible constant effect on the distance the firing valve 28 is opened, the length of time that the firing valve 28 remains open progressively increases as the pressure in the storage chambers 15 and 16 decreases. Thus, from both theoretical calculations and from the actual measurements of muzzle velocities of projectiles, there is found to be only a total variation in the projectile muzzle velocities between the first and twelfth shot, of less than five percent, and generally this variation will be less than three percent. If it is desired to shoot, for example, twenty-five projectiles from the single air charge in the storage chamber, this can be readily done by varying the hammer weight and spring coefficient. The muzzle velocities will, of course, unless the capacity of the storage chambers or the pressures therein are increased, be lower than when only twelve shots are being fired, but the variation between the first and twenty-fifth shot will be very, very small and substantially the same percentage as set forth above. As a matter of fact, as many as eighty to a hundred projectiles have been shot from a gun of this invention, without any substantial variation in the muzzle velocities of the projectiles. It is extremely important that the K factor of the spring and the hammer weight be of the proper amounts and in the proper relationship, in order to obtain the desired results.

For example, with the gun of this invention it has been found from actual tests, with a fluid pressure in the storage chambers 15 and 16 of approximately 350 to 360 pounds per square inch, that the best results are obtained with a hammer weight of approximately .04 pound and a spring 71 having a K factor or stiffness coefficient of approximately 2.9 pounds per square inch. With this hammer weight and spring K factor, there was only a difference in muzzle velocities, between the first and tenth projectile, of seventeen feet per second. That is, the muzzle velocity varied from 578 feet per second to 561 feet per second. If the gun were constructed with a hammer of the same weight as before, but with a spring having a greatly increased K factor, such as nine pounds per square inch, the variation in pellet muzzle velocity, between the first to the tenth shot would be 140 feet per second, or a drop from 557 feet per second to 417 feet per second. Similar results are obtained if the hammer weight is materially increased or if both the hammer weight and the K factor of the spring are increased. If the weight of the hammer is too large, it will take the air pressure in the storage chamber a longer time to stop the forward momentum of the hammer and reverse its motion, so as to permit the valve to be closed and as a result a large percentage of the air in the storage chamber will flow into the gun barrel behind the shot, and there will not be enough air left in the storage chambers to fire a plurality of successive shots at substantially the same muzzle velocity. Furthermore, if the hammer spring is not properly calibrated and has too large a K factor, it will increase the momentum or forward throw of the hammer to such an extent that the time the firing valve re-

mains open will be too much to permit a plurality of successive shots to be fired at substantially the same muzzle velocity.

It will, therefore, be seen that the hammer weight and the K factor of the hammer spring are extremely important in the construction of an air gun of the repeater type. It will furthermore be understood that the gun must be constructed so that the firing valve will only remain open a small and predetermined amount of time, each time it is struck by the hammer and plunger arrangement. This time will, of course, vary in accordance with the pressure in the storage chambers 15 and 16, but no one heretofore has ever developed an air gun in which the length of time the firing valve remains open is controlled accurately and in such a manner as to produce the results set forth above. This failure in the past has resulted not only from a failure to obtain the proper relationship between the hammer weight and spring K factor, but also because no one in the past has provided an air gun in which the air pressure in the storage chamber is relied upon almost entirely to absorb the energy and momentum of the hammer and cause the firing valve to close, and because no one in the past has constructed a gun in which the hammer is free floating or engages the valve stem or plunger while being free of the hammer spring. If the hammer spring followed the hammer throughout its entire forward movement, its compressed energy would have to be overcome by the air pressure in the storage chamber before the direction of movement of the hammer could be reversed. The length of time for closing the valve 28 with such a construction would be so long that the aforementioned repeating conditions could not be obtained. It should also be appreciated that the gun of this invention is of the hand-carriable type, and does not require the use of a mechanically driven compressor or the like. This gun thus provides a simple, relatively inexpensive and efficient repeating air gun which, after the air chamber has once been charged, can fire a plurality of projectiles at substantially the same muzzle velocity, and which at the same time can be easily carried by the user to any desired place, without the necessity of carrying along a separate compressor unit.

Slight variations in the range of muzzle velocities of the projectiles may be obtained by varying the kinetic energy of the hammer 69. This may be easily accomplished by a user of the gun with the construction illustrated in Figure 11 of the drawings, wherein it will be noted that the head 70 on the hammer 69 is formed with axially spaced shoulders 101 and 102. The arrangement is such that in one rotative position of the hammer 69, the shoulders 101 are respectively engaged by the block 86, and the sear 72, while in another rotative position of the hammer 69, the shoulders 102 are positioned for engagement by the block 86 and sear 72. When the shoulders 101 are in operative relationship to the block and sear, the spring 11 is compressed to a greater extent than when the shoulders 102 are in their operative position, so that the hammer 69 is moved forwardly with a greater velocity. Thus the head 30 on the valve member 28 is moved a greater distance away from the seat 31, and the time the valve 28 remains open is correspondingly increased. However, the difference in length of time the valve will remain open, as compared with the length of time previously discussed is so slight that it will

not affect the repeating characteristics of the gun. The primary purpose of the hammer adjustability feature is to permit the projectiles to be shot in a lower velocity range, which may be desirable with certain types of shooting, such as indoors, or the like. The two muzzle velocity ranges permitted with this construction are, furthermore, not widely separated from each other.

10 In instances where a hammer having axially spaced shoulders is employed, the rear end of the rod 65 projects through the breech plug 67, and is polygonally shaped in cross section. As shown in Figure 9 of the drawings, a sleeve 103 extends through the breech plug for slidably receiving the rear end of the rod, and relative rotation between the sleeve and the rod 65 is prevented by a set screw 104 carried by the sleeve, as can be clearly seen in Fig. 10. A control knob 105 is positioned on the rear end of the sleeve 103 for convenient manipulation by the operator, and is secured to the sleeve by a set screw 106. The arrangement is such that rotation of the knob 105 imparts a corresponding rotation to the rod to locate one or the other of the sets of shoulders 101 and 102 on the hammer in operative position with respect to the block 86 and sear 72. Thus, the projectile muzzle velocity range may be varied by merely adjusting the knob 105.

30 The modified air gun construction illustrated in Figs. 14 through 18 is similar in many aspects to that previously described and parts of this construction generally similar to parts in the previous construction are indicated by double primed numbers corresponding to those of the previous embodiment. The gun comprises a stock 11'' and a frame 12'' which is secured to the stock in any suitable manner such as by means of screws 13''. The frame comprises a barrel 14'', a main storage chamber 15'' and a secondary storage chamber 16'' communicating with the main chamber through a port 17''. The storage chamber 15'' is connected to the tubular compartment or chamber 24'' in the same manner as in the previous embodiment. The flow of air under pressure from the storage chamber 15'' to the barrel 14'' is controlled by the valve 28'', which is substantially the same as that previously described.

50 The compressor 32'' illustrated in this embodiment of the invention is of a slightly different form than that previously described, but it still forms a unit with the gun and is manually operable to supply fluid under pressure to the storage chambers 15'' and 16''. The compressor 32'' is generally similar to that illustrated and described in the copending patent application of Charles F. Lefever for improvements in Pressure Producing Device for Pneumatic Guns, Serial No. 32,880, filed June 14, 1948, and includes a cylinder 111 having a piston assembly 113 slidably supported therein. An annular shoulder or stop 115 is provided in the cylinder 111, intermediate the ends thereof, and the shoulder is centrally apertured at 117. The rear end of an operating rod 119 is threadably connected to the piston 113 and has a longitudinally extending passageway 121 therein, which is enlarged, at 123, at the extreme inner or rear end thereof, for the reception of a ball 125. The ball 125 is prevented from moving out of the open end of the enlarged aperture portion 123 by means of a pin 127. The forward end of the rod passageway 121 communicates with the cylinder 111

through a vertically extending passageway 131. The front end of the cylinder 111 is closed by means of a cap 135 which is threadably connected with a sleeve-like member 137, which in turn is threaded into the forward end of the frame 12 at 139. The forward end of the cylinder 111 fits into the rear end portion of the sleeve member 137 and is secured thereto in any suitable manner such as by soldering, or the like. The cap 135 is centrally apertured so as to slidably receive the rod 119 and a ball-type detent 141 is provided in the cap 135 for engagement with an annular groove 143, adjacent the forward end of the rod 119, so as to releasably hold the same in its innermost position. A foot engaging member 145 is pivotally connected at one end to an enlargement or head 147 on the forward end of the rod 119, outwardly of the cap 135. Movement of the rod 119 and piston 113, inwardly and outwardly, is limited by the cap 135 and the cylinder shoulder 115.

Rearwardly of the cylinder shoulder 115 a check valve 151 is provided which includes a valve stem 153 and a valve head 155, mounted on the stem, intermediate the ends thereof. The rear end of the valve stem 153 is slidably supported in an aperture 157 of a second cylinder shoulder or abutment 159. A coil spring 161 is mounted on the valve stem 153 between the cylinder shoulder 159 and the valve head 155, so as to resiliently hold the valve head 155 in sealing engagement with the back face of the cylinder shoulder 115, and thereby normally close passageway 117 against the flow of air therethrough. When it is desired to compress air in the storage chambers 15" and 16" the gun is placed in an inverted vertical position, so that the user can place a portion of his foot on the rod foot-engaging member 145. When the body of the gun is pulled upwardly away from the held member 145, atmospheric air in the forward end of the cylinder 111 passes through the rod passageways 131 and 121, forces the ball 125 off its seat and flows through enlarged passageway 123, where it is stopped by check valve 151. When the body of the gun is moved downwardly, air is compressed behind the piston 113, as the ball 125 will immediately be seated by the trapped air. When sufficient pressure has been built up, the valve 151 will be unseated so as to permit the air to flow into the cylinder 111 behind the valve. The air in the rearward portion of the cylinder can then flow through a cut out portion or notch 165 in the wall of the cylinder 111, into the annular space between the cylinder wall and the frame of the gun, and thence down through port 17" and into the secondary storage chamber 16". The compressor unit enables the storage chambers 15" and 16" to be charged with air under suitable pressure in a minimum length of time and with practically no leakage. The forward end of the cylinder 111 is replenished with atmospheric air in any conventional manner, such as by air leakage between rod 119 and cap 135 and/or through suitable cylinder openings.

The forward end of the secondary storage chamber 16" is closed by means of a cap 167 which is centrally apertured to receive a headed pin 169. The pin 169 has, adjacent its forward end, indicia thereon in the form of different colored bands or stripes 171. A plunger or piston 173 is connected to the rear portion of the pin 169 and a coil spring 175 extends between the cap 167 and the piston 173. When sufficient

pressure is built up in the storage chambers 15" and 16", the piston 173 will be moved forwardly thereby against the action of the spring 175, so as to make the stripes or bands 171 visible from the exterior of the gun. The spring 175 is so calibrated that when the desired pressure in the storage chambers is reached, the rearwardmost band or stripe 171 will be visible, and when the pressure in the storage chambers is below the desired or necessary amount, the bands or stripes, or at least the rearwardmost stripe, will not be visible to the user. In this way, a user who has charged the gun and fired only a few shots therefrom, before putting the gun away for a considerable period of time, will not, when he picks the gun up again, be in doubt as to whether or not there is sufficient air pressure in the storage chambers to shoot the gun in the desired manner.

The valve plunger 29", as previously described, is slidably supported in the rear portion of the compressor cylinder 111 in generally the same manner as previously described, and is yieldably held in a position at the rear end of the cylinder so that the pad 30" thereof engages the valve seat 31", by means of the light coil spring 62". The spring 62" acts in the same manner as in the previous embodiment. In order to open the valve 28" and connect the storage chambers to the gun barrel, rearwardly of a positioned projectile 19", the plunger or stem 60", having an enlarged head 61", the anvil 64", rod 65", hammer 69" and hammer spring 71" are provided in exactly the same manner as previously described. The hammer 69" is provided with the enlarged annular shoulder 70" at the rear end thereof for engagement by the bifurcated trigger sear 72" which is adapted to be actuated by a trigger mechanism 151 of any conventional or suitable type. The valve 28" is opened by the engagement of the hammer with the anvil, after release by the trigger mechanism, in substantially the same manner as previously described.

The rear end of the barrel 14" extends into and is connected with a breech block 183 which in turn is connected with the frame of the gun in any suitable manner, above the compartment 24". A magazine 185, in the form of a cylindrical passageway in the block 183, is provided adjacent to and in substantially the same horizontal plane, as the barrel 14". A magazine tube 187, in which a plurality of pellets 19" are stored in end to end relationship, has its opened end inserted into the forward end of the magazine 185 and its closed end connected with suitable bracket means (not shown) on the barrel, whereby the tube may be easily removed from the magazine for refilling. The rear end of the magazine communicates with the barrel 14" through a transversely extending recess or notch 193 in the breech block 183, as is generally illustrated and described in the copending patent application of Charles F. Lefever for improvements in Loading Mechanism for Pneumatic Guns, Serial No. 39,397, filed July 19, 1948, and now Patent Number 2,594,185. The recess or pocket 193 has a width slightly greater than the length of one of the pellets 19" and the breech end of the barrel 14" opposite the recess 193 is slotted at 191 to receive one of the pellets.

The pellet in the magazine, immediately adjacent to the rearmost pellet therein is held against movement toward the recess 193 by means of a pin 197, which is slidably supported in a vertical bore formed in the top of the breech block 183 and positioned to extend into the delivery

end of the magazine at a point to engage in the groove formed between the head and skirt portions of the aforementioned pellet. The upper end of the pin 197 is secured to a transversely extending leaf spring 199, which has one end secured to the breech block by any suitable means such as a screw 201, so that the leaf spring normally holds the pin in the vertical bore above the magazine. The leaf spring 199 is actuated, so as to move the pin downwardly into the magazine, by means of an arm member 203. The arm 203 is pivoted at its front end to the breech block 183 by means of pin 205 and the rear portion of the arm is slotted to provide two furcations 207 and 209. An angle shaped projection 211 extends downwardly from the arm furcation 207 into the breech block recess 193 for the purpose of transferring pellets from a position in the recess, at the delivery end of the magazine, to a position within the breech end of the barrel 14.

An inverted, generally channel-shaped slide member 213 is slidably connected to the upper portion of the gun frame 12" by any suitable means so as to normally cover the breech block 183 and arm 203. A cam 215 is connected to one of the vertical side wall portions of the slide 213 and is adapted, when the slide is pushed to its forwardmost position, to engage a cam surface 217 formed on the outer edge of the arm furcation 209, so as to normally hold the arm in such a position that the downwardly extending projection 211 thereof is disposed laterally outwardly of the magazine 185. A hairpin type spring 219 is connected between the arm 203 and the breech block 183 for urging the arm projection 211 towards the barrel, when the slide 213 is pulled rearwardly.

The upper wall of the compartment 24" is provided with a longitudinally extending slot 219 in which is slidably mounted a block 221, which is connected to the slide 213 by means of screw 223. The block 221 is provided with a downwardly extending pin 225, which is disposed forwardly of the hammer shoulder 70" so that when the block moves rearwardly it will move the hammer shoulder 70" rearwardly beyond the trigger sear 72", in order to cock the gun. Projecting forwardly from the block 221 is a pin 227 which is slidably received in the rear end of the barrel 14". The forward end of the pin 227 is tapered and reduced in diameter at 229 and positions a pellet 19" in the barrel ahead of the compressed air vertical passageway 27", as will be hereinafter described. Connected to the pin 227 intermediate the ends thereof, is a plate 233, the forward portion of which is notched or cut back to provide a furcation 235. When the slide 213 and block 221 are in their forwardmost position, after for example, a projectile has been fired, and it is desired to load and cock the gun, the forward end of the barrel is tilted upwardly and as the downwardly extending projection 211 of the arm 203 is disposed laterally outwardly of the delivery end of the magazine, the rearmost projectile in the magazine will drop rearwardly into the breech block recess 193. The pin 197 will prevent the adjacent projectile in the magazine from dropping into the recess, due to the fact that it is pressed downwardly by the arm 203. The projectile will be properly positioned in the recess 193 by the furcation 235 on the forward end of the plate 233.

When the slide 213 is pulled rearwardly the plate 233, pin 227 and block 221 will move rearwardly, as well as the slide cam 215. The hairpin

spring 219 will then cause the downwardly extending projection 211 to sweep across the recess 193 and position the pellet in the slotted portion 191 of the barrel. At the same time, the downwardly extending pin 225 on the block 221 will move the hammer shoulder 70" past the upper furcation of the trigger seal 72", so as to hold the same in its cocked position. When the downwardly extending projection 211 has swept across the recess 193, the spring loaded pin 197 will move out of engagement with the projectile in the magazine and will permit the projectile to move to the rear end of the magazine and into engagement with the projection 211 on the arm 203.

When the slide is pushed forwardly again, the slide cam 215 will move the downwardly extending projection 211 of the arm 203 back across the recess and out of interference with the delivery end of the magazine and the rearmost projectile in the magazine can drop into the recess 193. Again, the pin 197 has been pressed downwardly into the magazine to keep the next projectile therein. The forward movement of the slide 213 will cause the forward end of the pin 227 to move the pellet, in the breech end of the barrel, forwardly beyond the passageway 27", as indicated in dot and dash lines in Fig. 14. The gun is then ready for firing. When the trigger is pulled, the hammer is released and thrown forwardly by the spring 71" against the anvil 64" and the valve 28" is opened in the manner previously described.

It will thus be seen that the gun of this embodiment is automatically loaded and cocked at the same time, so that it is not necessary to drop a projectile into the barrel each time the gun is cocked, as with the previous embodiment. It will also be appreciated that with the construction of this embodiment, means are provided for indicating to the user of the gun when the air pressure in the storage chambers 15" and 16" is below the desired amount, and a novel type of compressor unit is illustrated. However, it will be appreciated that the valve 28" is opened, and operates, in exactly the same manner as previously described, so that the gun of this embodiment is of the repeater type, for the same reasons and in the same manner set forth above.

What is claimed is:

1. A repeater type pneumatic gun including a barrel through which a projectile may be shot, a storage chamber communicating with said barrel and adapted to contain a volume of fluid at a relatively high pressure, valve means between said barrel and storage chamber for controlling the flow of fluid from the chamber to said barrel, said valve means being normally held in a closed position by the fluid pressure in said chamber, a hammer member supported in said gun for movement toward and away from said valve means in substantially the same direction as the direction of movement of said valve means and adapted to engage said valve means and open the same against the fluid pressure in said chamber, means for actuating said hammer member and moving the same towards said valve means, said means including a spring element engaging said hammer member only during a portion of its movement toward said valve means, whereby said means will be disengaged from said hammer member before said valve means is engaged by said hammer member and opened.

2. A repeater type pneumatic gun including a barrel through which a projectile may be shot, a storage chamber communicating with said bar-

rel and adapted to contain a volume of fluid at a relatively high pressure, valve means between said barrel and storage chamber for controlling the flow of fluid from the chamber to said barrel, said valve means being normally held in a closed position by the fluid pressure in said chamber, a hammer member supported in said gun for movement toward and away from said valve means in the same direction as the direction of movement of said valve means and adapted to engage said valve means and open the same against the fluid pressure in said chamber, means for actuating said hammer member and moving the same towards said valve means, said means including a spring element engaging said hammer member only during a portion of its movement toward said valve means, whereby said means will be disengaged from said hammer member before said valve means is engaged thereby and opened, the movement of said hammer member toward said valve means and the movement of said hammer and said valve means after said valve means has been engaged by said hammer member, being substantially unimpaired except by the fluid pressure in said chamber against which said valve means is opened.

3. A repeater type pneumatic gun including a barrel through which a projectile may be shot, a storage chamber communicating with said barrel and adapted to contain a volume of fluid at a relatively high pressure, valve means between said barrel and storage chamber for controlling the flow of fluid from the chamber to said barrel, said valve means being normally held in a closed position by the fluid pressure in said chamber, a hammer member supported in said gun for movement toward and away from said valve means and adapted to engage said valve means and open the same against the fluid pressure in said chamber, means for actuating said hammer member and moving the same towards said valve means, said means including a spring element engaging said hammer member only during a portion of its movement toward said valve means, whereby said means will be disengaged from said hammer member before said valve means is engaged thereby and opened, said hammer member and valve means being movable in the direction of actuation of said hammer by said resilient means until the momentum thereof is overcome by the fluid pressure in said chamber, at which time the fluid pressure will move said valve means and hammer member in the opposite direction and close said valve means.

4. A pneumatic gun including a barrel through which a projectile is adapted to be shot, a storage chamber adapted to contain a volume of fluid and communicating with said barrel, said gun being of the type adapted to shoot a plurality of projectiles from the barrel after said storage chamber is initially charged with fluid under pressure, said chamber having a fluid capacity such as to be capable of supplying the fluid necessary to propel a predetermined number of projectiles from said barrel all at a substantially constant velocity, valve means between said barrel and storage chamber for controlling the flow of fluid from said chamber to said barrel, said valve means being normally held in a closed position by the fluid pressure in said chamber, a hammer member supported in said gun for movement toward and away from said valve means and adapted to engage said valve means and open the same against the fluid pressure in said chamber, means for actuating said hammer member and

moving the same toward said valve means, said means including a spring element engaging said hammer member only during a portion of its movement toward said valve means whereby said 5. means will become disengaged therefrom prior to the engagement of said valve means by said hammer member, the weight of said hammer member and the force factor of said spring element being correlated such as to open the valve means a 10. plurality of times, such amounts and for such periods of time as to permit a plurality of projectiles to be propelled from said barrel by fluid pressure from said chamber, without recharging the pressure in said chamber, at substantially the 15. same muzzle velocity, but in no case at a muzzle velocity variance of more than twenty percent.

5. A pneumatic gun including a barrel through which a projectile is adapted to be shot, a storage chamber adapted to contain a volume of fluid and communicating with said barrel, said gun being of the type adapted to shoot a plurality of projectiles from the barrel after said storage chamber is initially charged with fluid under pressure, said chamber having a fluid capacity such as to be capable of supplying the fluid necessary to propel a predetermined number of projectiles from said barrel all at a substantially constant velocity, valve means between said barrel and storage chamber for controlling the flow of fluid from said chamber to said barrel, said valve means being normally held in a closed position by the fluid pressure in said chamber, a hammer member supported in said gun for movement toward and away from said valve means and adapted to engage said valve means and open the same against the fluid pressure in said chamber, resilient means movable from a compressed position to an uncompressed or free position to actuate said hammer member and move the same toward said valve means, the length of travel of said resilient means from its compressed to uncompressed position being less than the distance the hammer member moves to engage said valve means so that said resilient means becomes disengaged from said hammer member prior to the engagement of said valve means by said hammer member, the mass of said hammer member and the force exerted by said resilient means being so related to the pressure in said storage chamber and the mass and size of said valve means as to open said valve means a predetermined distance and for a predetermined length of time, in accordance with the pressure in said chamber, so as to propel said plurality of projectiles from said barrel at a substantially uniform muzzle velocity, and to permit only the necessary volume of fluid to flow to the barrel each time said valve means is opened such that the necessary volume of fluid, at a sufficiently high pressure, will be present in the storage chamber to propel the last of said predetermined number of projectiles from said barrel at substantially the same muzzle velocity as the prior projectiles propelled from said charge of fluid.

65 6. A pneumatic gun including a barrel through
which a projectile is adapted to be shot, a stor-
age chamber adapted to contain a volume of fluid
and communicating with said barrel, said gun
being of the type adapted to shoot a plurality of
70 projectiles from the barrel after said storage
chamber is initially charged with fluid under
pressure, said chamber having a fluid capacity
such as to be capable of supplying the fluid neces-
75 sary to propel a predetermined number of pro-
jectiles from said barrel all at a substantially con-

stant velocity, valve means between said barrel and storage chamber for controlling the flow of fluid from said chamber to said barrel, said valve means being normally held in a closed position by the fluid pressure in said chamber, a hammer member supported in said gun for movement toward and away from said valve means and adapted to engage said valve means and open the same against the fluid pressure in said chamber, resilient means movable from a compressed position to an uncompressed or free position to actuate said hammer member and move the same toward said valve means, the length of travel of said resilient means from its compressed to uncompressed position being less than the distance the hammer moves to engage said valve means so that said resilient means becomes disengaged from said hammer member prior to the engagement of said valve means by said hammer member, the weight of said hammer member and the force exerted by said resilient means being correlated relative to each other such as to open said valve means for a predeterminedly greater length of time as the pressure in said storage chamber drops predetermined amounts, so as to maintain the product of the length of time and the fluid pressure substantially constant for a predetermined number of shots from said gun, whereby to maintain a substantially uniform muzzle velocity for the plurality of projectiles shot from said gun.

7. A repeater type pneumatic gun including a barrel through which a projectile is adapted to be shot, a storage chamber communicating with said barrel and adapted to contain a volume of fluid at a relatively high pressure, valve means between said barrel and storage chamber for controlling the flow of fluid from the chamber to said barrel, said valve means including a valve seat and a valve member normally urged into engagement with the valve seat by the fluid pressure in the storage chamber, a hammer member supported in said gun for movement toward and away from said valve means, means for moving said hammer member toward said valve means, an anvil supported in said gun for moving toward and away from said valve means and engageable by said hammer member for delivering an impact to said valve member sufficient to move the latter away from its seat against the fluid pressure in said storage chamber, said hammer moving means including a resilient element movable from a compressed to an uncompressed position to actuate said hammer member and move the same toward said anvil, the length of travel of said resilient element from its compressed to uncompressed positions being less than the distance the hammer member moves to engage said anvil so that said resilient element will become disengaged from said hammer member before the latter engages said anvil.

8. A repeater type pneumatic gun including a barrel through which a projectile is adapted to be shot, a storage chamber communicating with said barrel and adapted to contain a volume of fluid at a relatively high pressure, valve means between said barrel and storage chamber for controlling the flow of fluid from the chamber to said barrel, said valve means including a valve seat and a valve member normally urged into engagement with the valve seat by the fluid pressure in the storage chamber, a hammer member supported in said gun for movement toward and away from said valve means, means for moving

5 said hammer member toward said valve means, an anvil supported in said gun for movement toward and away from said valve means and engageable by said hammer member for delivering an impact to said valve member sufficient to move the latter away from its seat against the fluid pressure in said storage chamber, said hammer moving means including a resilient element movable from a compressed to an uncompressed position to actuate said hammer member and move the same toward said anvil, the length of travel of said resilient element from its compressed to uncompressed positions being less than the distance the hammer member moves to engage said anvil so that said hammer moving means will become disengaged from said hammer member before the latter engages said anvil, and said hammer, anvil and valve member being substantially free to move in the direction of actuation of said hammer member until the momentum thereof is overcome by the fluid pressure in the storage chamber, at which time the fluid pressure will return said valve member into engagement with said valve seat without having to overcome any force exerted by said resilient element.

9. A pneumatic gun including a barrel through which a projectile is adapted to be shot, a storage chamber adapted to contain a volume of fluid and communicating with said barrel, said gun being of the hand-carriable repeater type adapted to shoot a plurality of projectiles from the barrel at a substantially uniform muzzle velocity after said storage chamber is initially charged with fluid under pressure, valve means between said barrel and storage chamber for controlling the flow of fluid from said chamber to said barrel, said valve means being normally held in a closed position by the fluid pressure in said chamber, a hammer member slidably supported in said gun for movement toward and away from said valve means and adapted to engage said valve means and open the same against the fluid pressure in said chamber, a spring element adapted to be cocked and released so as to propel 40 said hammer member toward said valve means as a free-floating mass, said spring element engaging said hammer member only during a portion of its movement toward said valve means, said hammer member being free to move substantially unimpaired toward and into engagement with said valve means, and said valve means being free to move substantially unimpaired except by the fluid pressure away from said valve seat so that the propelled movement 45 of said hammer member mass will be uninterrupted until said hammer member opens said valve means and the momentum thereof is overcome by the fluid pressure in the storage chamber, at which time the fluid pressure will close 50 said valve means and reverse the direction of movement of said hammer member.

10. A hand-carriable repeater type pneumatic gun including a barrel through which a projectile may be shot, a storage chamber communicating with said barrel and adapted to contain a volume of fluid at a relatively high pressure, means for compressing air in said storage chamber at a desired pressure, valve means between said barrel and storage chamber for controlling the flow of fluid from the chamber to said barrel, said valve means being normally held in a closed position by the fluid pressure in said chamber, a hammer member supported in said gun for movement toward and away from said 70 valve means and adapted to engage said valve

means and open the same against the fluid pressure in said chamber, resilient means supported in said gun adjacent said hammer member and movable from a compressed to an uncompressed position to actuate said hammer member and move the same toward said valve means, the length of travel of said resilient means from its compressed to uncompressed positions being less than the distance said hammer member moves to engage said valve means so that said resilient means will become disengaged from said hammer member before said valve means is engaged by said hammer member and opened.

11. A pneumatic gun including a barrel through which a projectile is adapted to be shot, a storage chamber adapted to contain a volume of fluid and communicating with said barrel, said gun being of the type adapted to shoot a plurality of projectiles from the barrel after said chamber is initially charged with fluid under pressure, said chamber having a fluid capacity such as to be capable of supplying the fluid necessary to propel a predetermined number of projectiles from said barrel, all at a substantially constant velocity, valve means between said barrel and storage chamber for controlling the flow of fluid from said chamber to said barrel, said valve means being normally held in a closed position by the fluid pressure in said chamber, a hammer member supported in said gun for movement toward and away from said valve means and adapted to engage said valve means and open the same against the fluid pressure in said chamber, resilient means supported in said gun and movable from a compressed to an uncompressed position to actuate said hammer member and move the same toward and into engagement with said valve means, the length of travel of said resilient means from its compressed to uncompressed positions being less than the distance said hammer member moves to engage said valve means, so that said resilient means becomes disengaged from said hammer member before the latter engages said valve means, said hammer member having a weight and said resilient means exerting a force against said hammer member which will maintain the product of the length of time the valve means remains open and the fluid pressure flowing to said barrel substantially constant for a predetermined number of shots from said gun, whereby to maintain a substantially uniform muzzle velocity for the plurality of projectiles shot from the gun.

12. A pneumatic gun including a barrel through which a projectile is adapted to be shot, a storage chamber adapted to contain a volume of fluid and communicating with said barrel, said gun being of the type adapted to shoot a plurality of projectiles from the barrel after said storage chamber is initially charged with fluid

under pressure, said chamber having a fluid capacity such as to be capable of supplying the fluid necessary to propel a predetermined number of projectiles from said barrel, all at a substantially constant muzzle velocity, valve means between said barrel and storage chamber for controlling the flow of fluid from said chamber to said barrel, said valve means being normally held in a closed position by the fluid pressure in said chamber, a hammer member supported in said gun for movement toward and away from said valve means and adapted to engage said valve means and open the same against the fluid pressure in said chamber, spring means including a spring portion for actuating said hammer member and moving the same toward said valve means, said spring portion being movable from a compressed to an uncompressed position to actuate said hammer member and move the same toward and into engagement with said valve means, the length of travel of said spring portion from its compressed to uncompressed positions being less than the distance the hammer member moves to engage said valve means, so that said spring portion becomes disengaged from said hammer member prior to the engagement of said valve means by said hammer member, the weight of said hammer member and the force of said spring being such as to open said valve means a predetermined amount and for a predetermined period of time each time said valve means is engaged by said hammer member, and such as to open said valve means a greater distance and for a longer period of time as the fluid pressure in said storage chamber decreases, whereby, as the pressure in said storage chamber decreases, said valve means will be opened for a greater period of time to permit a larger volume of fluid at a lower pressure to be communicated to the barrel behind the projectile therein and shoot the projectile from the barrel at substantially the same muzzle velocity as the projectile fired before and the projectile fired thereafter.

WILLIAM S. WELLS.
